CUSTARD TRAY

Richard F. Reifers, New Canaan, Conn., assignor to Diamond Gardner Corporation, New York, N.Y., a corporation of Delaware

Application June 4, 1959, Serial No. 56,202

Term of patent 14 years

(Cl. D44—10)

Fig. 1 is a view in perspective of a custard tray showing my new design.

Fig. 2 is a view in side elevation with parts in vertical section taken along line 2—2 of Fig. 1.

I claim:

The ornamental design for a custard tray, as shown.
